YARN-SUPPLYING MECHANISM

Paul S. Smith, Rockford, Ill., assignor, by mesne assignments, to Ellen Bertha Allen, Birmingham, Mich.

Original application July 15, 1940, Serial No. 345,448. Divided and this application April 17, 1942, Serial No. 439,439

6 Claims. (Cl. 271—2.1)

This application is a division of my co-pending application, Serial No. 345,448, filed July 15, 1940, for Apparatus for making cemented pile fabric, upon which U. S. Patent No. 2,302,702, was granted November 24, 1942, that is to say, apparatus for use in the manufacture of that type of pile fabric in which the fibers forming the pile are attached to a backing fabric by cementing material. The invention of said application relates to improvements upon the apparatus disclosed and claimed in United States Letters Patent, No. 2,050,740, patented to me on August 11, 1936, and the apparatus forming the subject-matter of said application is useful in carrying out the method disclosed and claimed in United States Letters Patent, No. 2,051,010, also patented to me on August 11, 1936. The present application relates to improvements in yarn-supplying mechanism forming a part of said apparatus, but which I believe to be useful in other connections.

It has long been known that pile fabric may be manufactured by cementing the fibers forming the pile to a backing sheet, or fabric, and the usual practice has been to attach such fibers to the backing sheet in looped form with the loop portions of the pile fibers cemented to the backing sheet. Such fibers may be applied either in the form of yarn or as unspun fibers. The principal object of the invention forming the subject of my said application, Serial No. 345,448, (Patent No. 2,302,722) was to provide an improved apparatus by means of which such cemented pile fabric can be manufactured at a lower cost than is possible by apparatus heretofore proposed for use.

The principal object of my present invention is to provide a yarn-supplying or warp draw-off mechanism which creates and maintains a slack supply of yarn or warp, that is particularly useful in connection with a machine for making cemented pile fabric, including a plaiting mechanism, in that the tension on the several yarns of the warp supplied to the plaiting mechanism will be a minimum, corresponding only to the effort of drawing the yarns from the draw-off mechanism, thus entirely relieving the plaiting mechanism of the considerable work of drawing the warp from a beam or creel and resulting in a better product.

A further object of my invention is to provide a yarn-supplying mechanism which includes a clamp and a pair of loop-forming devices, one on either side of the clamp, and means for operating the clamp and the loop-forming devices in such

timed relation as to create and maintain a slack supply of yarn to feed the machine in which the yarn is used.

Further objects, and objects relating to details of construction and economies of manufacture, will definitely appear from the detailed description to follow. In one instance, I have accomplished the objects of my invention by the devices and means set forth in the following specification. My invention is clearly defined and pointed out in the appended claims. A structure constituting a preferred embodiment of the invention is illustrated in the accompanying drawings, forming a part of this specification, in

15 which:

Figure 1 is a view in front elevation of a portion of the machine for making cemented pile fabric in connection with which my improved yarn-supplying mechanism is used;

20 Fig. 2 is a top plan view of the yarn-supplying mechanism;

Fig. 3 is a detail sectional view taken on the line 3—3 of Fig. 2;

25 Fig. 4 is a vertical sectional view, on an enlarged scale, through the yarn-supplying mechanism; and

30 Fig. 5 is a detail view in vertical section illustrating one of the actuating cams and its connections to one of the loop-forming devices of the yarn-supplying mechanism.

In the drawings, similar reference numerals refer to similar parts throughout the several views and the sectional view is taken looking in the direction of the arrows at the ends of the section line.

35 In a machine for making cemented pile fabric by plaiting a warp of yarn about severable separator strips, I have found it highly desirable that the warp of yarn should be fed to the plaiting mechanism in a slack condition. To accomplish this, I have provided a warp draw-off or yarn-supplying mechanism, which performs the work of drawing yarn or warp from a creel or beam and, at the same time, creates and maintains a slack supply from which the plaiting mechanism draws. This mechanism comprises a clamping device, through which the warp passes and which is opened and closed to release and grip the yarn. I provide two loop-forming devices, one operating in advance of the clamping device and the other on the other side thereof. The operation of these loop-forming devices is so timed with relation to the operation of the clamping device that, when the clamping device is closed, the loop-forming device in advance thereof operates to draw yarn

from a source of supply and form a loop of slack yarn or warp in advance of the clamping device.

The operation of the second loop-forming device is so timed that, when the clamp is opened, it will draw through the clamp warp or yarn from the loop previously formed by the first loop-forming device, so as to create a loop or slack supply of yarn for which the plaiting mechanism draws as needed. The plaiting mechanism thus operates at all times on a warp consisting of individually slack yarns.

Referring to the numbered parts of the drawings, upon a base (not shown) there are mounted two side members 37 and 38. Each of these side members consists of a pair of vertical pillars connected by cross members, as at 41. The side members 37 and 38 are tied together by the base and by various cross members. Mounted upon the upper ends of the pillars of side members 37 and 38, are transverse yokes 42 and 43, which tie said side members together. Secured to the tops of yokes 42 and 43 are the horizontal parallel rails 44, which support the yarn-supplying mechanism.

The power for operating the machine is transmitted to it by driving connections to the vertical shaft 48. On the upper end of shaft 48, there is a bevel pinion 49 meshing with the bevel gear 50, which is secured to the shaft 51, whereby that shaft is driven. Secured to shaft 48 is a spiral gear 52 meshing with a spiral pinion 53 on a cross-shaft 54. Shaft 54 carries another spiral pinion 55 meshing with a spiral gear 56 secured to retaining finger release shaft 57, whereby shaft 57 is driven. A worm 58 is also secured to shaft 54 and meshes with a worm gear 59 secured to yarn-supplying cam shaft 60, whereby that shaft is driven to actuate the cams for the yarn-supplying mechanism.

The yarn-supplying or warp draw-off mechanism, forming the subject-matter of my present invention, creates and maintains a slack supply of warp or yarn for feeding the plaiting mechanism. This yarn-supplying mechanism comprises a pair of tension rolls 83, 84 (Fig. 1), each having trunnions 85, 86, at opposite ends, which rest in vertical slots 87 of brackets 88 secured to the rails 44. The yarns going to make up the warp A come from a suitable source of supply and pass underneath the lower tension roll 83, thence up and between the tension rolls 83 and 84, and over the top roll 84, to the yarn-supplying mechanism. A guide roll 89 is also provided, journaled in brackets 90 mounted on the rails 44, and located substantially vertically above the mouth of the confining passage in which the plaited structure is to be formed. The warp A passes over the guide roll 89, thence through the plaiting mechanism to the mouth of the confining passage and, as the plaited structure is formed about the strips in the mouth of said passage, the warp is drawn from the slack supply created and maintained by the yarn-supplying mechanism in advance of the guide roll 89.

The yarn-supplying mechanism includes a clamping device through which the warp passes, which clamping device is adapted to be closed to grip the yarns of the warp and opened to release them. This clamping device includes a lower clamping bar 91 (Fig. 4), secured to and extending transversely between the rails 44. Vertical studs 92 are screwed into the ends of bar 91 and the channel member 93, forming the upper member of the clamping device, is slidably mounted on the studs 92, having sleeves 94

secured thereto which are slidable on the studs 92. Compression springs 95 surround the sleeve 94 and are compressed between the base of channel member 93 and nuts screwed on the upper ends of the studs 92. These springs normally bring the upper member 93 of the clamping device into clamping engagement with the bar 91 thereof. A bar 96 is secured to the bottom of member 93 by screws 97 and is enveloped in a sheet 98 of suitable material, such as emery-cloth, so as to provide a surface which will grip well upon the yarns of the warp passing through the clamping device.

At each end of the clamping device, there is a lever 99 pivoted at 100 in a bracket 101, mounted on the corresponding rail 44. Each of these levers is pivotally connected by a pin 102 (Fig. 3) with the adjacent end of the upper clamping member 93. The outer end of each lever 99 (Fig. 4) is pivotally connected at 103 with the upper end of a link 104, the lower end of which is pivoted to a rocker arm 105, journaled on shaft 106, which is carried by and extends between the frame members 37 and 38. Each rocker arm 105 carries a roller 105' engaging an edge cam 107, fast on the cam shaft 60.

Fixed in brackets 108, secured to the side of the upper clamping bar 93, are pins 109, which extend downwardly alongside the lower clamping bar 91, and are so located as to serve as edge guides for the warp of yarn passing through the clamping device.

The first loop-forming bail is located between the rollers 83, 84, and the clamping device, and the warp of yarn, as it leaves said rollers, passes beneath the said bail and thence between the lower clamping bar 91 and the upper clamping bar 93. A shaft 110 is journaled in brackets 40 111 (Fig. 2), mounted on the side rails 44. The arms 112 of the bail are secured to shaft 110, and support the roller bail 113, which extends above the warp of yarn, as shown in Fig. 2. Operating arms 114, one at each side, are secured to shaft 110, and these arms are pivotally connected to the upper ends of links 115 (Fig. 4), the lower ends of which are pivoted to rockers 116 journaled on shaft 106. Each rocker carries a roller 117, which engages the edge of a corresponding cam 118, fixed on cam shaft 60. It will be noted that the shape of cams 118 is such that there is a comparatively slow rise from the low to the high spot of the cam, and a quicker return from said high spot to the low spot. Thus, as the cam rotates in the direction of the arrow indicated in Fig. 1, the links 115 are raised rather slowly, thus slowly rocking the bail 113 upward. The bail is maintained in its upper position by the high surfaces of the cams which occupy about one-third of the cam peripheries. The shape of the cams is such that the bail is returned more rapidly from its high position to the low position illustrated in Fig. 4.

Spring connections are provided which tend to rock the first loop-forming bail into the lower loop-forming position, shown in Fig. 4. These spring connections comprise sectors 119, fixed to shaft 110 to which the upper ends of cables 121 are connected at 120. The lower ends of these cables are connected to tension springs 122, which, in turn, are connected to the upper ends of cables 123, the lower ends of which are fastened to rings in the base 35.

Guide fingers 125 (Fig. 2), having their rear ends bent back upon themselves, are secured as

at 126 to the bail arms 112, as shown in Figs. 2 and 4, and serve as edge guides for the warp passing under the bail.

The second loop-forming bail is located between the clamping device and the guide roller 89, and the warp of yarns A, as it leaves the clamping device, passes under said bail and, thence, over the roller 89 to the plaiting mechanism. Shaft 127 (Fig. 4) is journaled in brackets 128 secured to the side rails 44. The arms 129 of the second loop-forming bail are secured to shaft 127 and support the roller ball 130, under which the warp of yarns passes. An operating arm 131 (Fig. 1) is secured to shaft 127 adjacent one of the side rails 44, and the lower end of this arm is connected to the upper end of a link 132, the lower end of which is connected at 141 (Fig. 5) to one arm 133 of a two-armed lever pivoted on shaft 134. The other arm 135 of this lever is connected to the upper end of a link 136, the lower end of which is pivotally connected to a rocker arm 137, journaled on shaft 106. Rocker arm 137 carries a roller 138, which engages the edge of a cam 139, fast on the cam shaft 60. Consideration of the shape of cam 139 will show that, as cam shaft 60 revolves, the second loop-forming bail is gradually lowered from the position shown in Fig. 1 to its lowermost position, drawing the warp of yarns through the clamping device, which is, at that time, opened, and, then, the roller ball is as gradually returned to its position. A spring 140, connected at one end to the pin 141, and, at the other end, to a bracket 142 (Fig. 1) on the side rail 44, tends to move the bail 130 to the lower position, and to hold roller 138 in contact with the edge of cam 139.

Referring to Fig. 4, a consideration of the contour of the clamp-operating cams 107 will show that the clamp remains open during about two-thirds of the cycle. Considering the contour of the cams 118, which operate the first loop-forming bail 113, it will be apparent that the bail moves upward slowly during about one-half of the cycle, dwells in its uppermost position during the ensuing one-third, and falls rapidly during the remaining one-sixth. Consideration of the relative timing of these cams will show that the clamp remains closed during the downward loop-forming movement of the bail 113 and remains open during its upward movement and dwell.

Referring to Figs. 4 and 5, and regarding one revolution of the cams 107, 118 and 139 as constituting a cycle of the draw-off mechanism, it will be noted that, in the position shown in Fig. 4, the bail 113 is in its lowest position, having completed the formation of a loop of warp, and the clamp is closed. Further revolution of the cams 107 and 118 will cause the clamp to open, and to remain open during about two-thirds of the cycle, while, at the same time, the bail 113 will rise gradually and dwell in its uppermost position during about five-sixths of the cycle. During this period, the major portion of the loop of warp thus formed may be drawn through the open clamp by the operation of the second loop-forming bail 130, and by the action of the plaiting mechanism. When the cam 118 has completed about five-sixths of a revolution from the position shown in Fig. 4, the cam 107 will have reached such a position as to have just closed the clamp, whereupon further rotation of the cam 118 permits the bail 113 to descend rapidly to

the position shown, forming a new loop in the warp, and completing the cycle.

Referring, now, to Fig. 5, it will be noted that the cam 139 has two symmetrical lobes and is thus adapted to produce uniform movement of the arms 129 of the second loop-forming bail 130, from the position shown in Fig. 4 downward to a position substantially at right angles thereto, and, similarly, to return them to their original positions, thus forming a loop of warp between the clamp and the roller 89. The cam 139 in Fig. 5 is shown substantially in timed relationship with cams 107 and 118 in Fig. 4. From the position shown, a slight further rotation of the shaft 60 will cause the cam 107 to open the clamp, while the cam 118 will begin to lift the bail 113 from the loop it has just formed. At the same time, the cam 139 will have raised the bail 130 to its highest position from which it will immediately commence to descend, drawing slack warp through the clamp to form a loop between the clamp and the roller 89, while, simultaneously, the plaiting mechanism draws the required slack warp from the loop released by the rising bail 113, through the open clamp, and under the descending bail 130. Shortly prior to the closing of the clamp, the bail 130 will have completed its downward movement and started to rise, which it will continue to do throughout the remainder of the cycle, while the plaiting mechanism supplies itself from the loop of slack warp previously formed by the descent of the bail.

It will be obvious that the bail 113 must be capable of forming a loop containing slightly more warp than is required by the plaiting mechanism during one cycle of the draw-off mechanism, and that the bail 130 must be capable of forming a loop containing slightly more warp than is required by the plaiting mechanism, during the period when the clamp is closed. Under these conditions, the draw-off device is inherently and automatically self-compensating, in that there will always be slack yarn available for the plaiting mechanism and, yet, in the long run, only the exact amount of warp required for an indefinite series of plaiting operations will be withdrawn from the source of supply.

In the specification, and the appended claims, the term "warp" is used as meaning either a warp of spun yarns or a bat of unspun fibers.

I am aware that the apparatus here shown is susceptible of considerable variation without departing from the spirit of my invention and, therefore, I claim my invention broadly as indicated by the appended claims.

What I claim is:

1. A yarn supplying mechanism comprising the combination of a clamping device through which the yarn passes, means for operating said clamping device to alternately grip and release said yarn, a first loop-forming device acting on the yarn in advance of said clamping device, means for actuating said first loop-forming device to draw yarn from a supply and form a first loop therein in advance of said clamping device as it grips the yarn and to move and remain out of engagement with said loop while the clamping device releases the yarn, a second loop-forming device acting on the yarn in the rear of said clamping device, and means for actuating said second loop-forming device to draw yarn from said first loop through said clamping device as it releases the yarn, to form a second loop in the

rear of said clamping device and to move and remain out of engagement with said second loop during most of the cycle.

2. A yarn supplying mechanism comprising the combination of a clamping device through which the yarn passes, means for operating said clamping device to alternately grip and release said yarn, a first loop-forming bail pivoted in advance of said clamping device, means for rocking said bail as said clamping device grips the yarn to cause said bail to engage and draw the yarn from a supply to form a first loop therein in advance of said clamping device and to recede therefrom leaving a free loop and for maintaining said bail out of engagement with said loop while the clamping device releases said yarn, a second loop-forming bail pivoted in the rear of said clamping device, and means for rocking said second loop-forming bail to cause it to engage said yarn while it is released to draw yarn from said first loop through said clamping device and form a second loop in rear thereof and for maintaining said second bail out of engagement with said second loop during most of the cycle.

3. A yarn supplying mechanism comprising the combination of a clamping device through which the yarn passes, spring means acting on said clamping device and tending to close the same to grip the yarn, means for opening said clamping device against the action of said spring means to release the yarn, a first loop-forming bail pivoted in advance of said clamping device, means for rocking said bail to cause it to act on and draw yarn from a supply to form a first loop therein in advance of said clamping device while the latter is closed by the spring means to grip the yarn and for maintaining said bail out of engagement with said first loop while the clamping device releases the yarn, a second loop-forming bail pivoted in the rear of said clamping device, and means for rocking said second bail while said clamping device is open to release the yarn, to cause said bail to engage the yarn and draw it from said first loop through said clamping device to form a second loop in the rear thereof, said last-named means being such as to maintain the second bail out of engagement with the second loop during most of the cycle.

4. A yarn supplying mechanism comprising the combination of a clamping device through which the yarn passes, means for operating said clamping device to alternately grip and release said yarn, a first loop-forming device acting on the yarn in advance of said clamping device, means for actuating said first loop-forming device to draw yarn from a supply and form a first loop therein in advance of said clamping device while it grips the yarn and to remain out of engagement with said loop while said clamping device releases the yarn, a second loop-forming device acting on the yarn in the rear of said clamping

device, and means for actuating said second loop-forming device to draw yarn from said first loop through said clamping device while it releases the yarn to form a second loop in the rear of said

5. A yarn supplying mechanism comprising the combination of a clamping device through which the yarn passes, means for operating said clamping device to alternately grip and release said yarn, a first loop-forming bail pivoted in advance of said clamping device, means for rocking said bail while said clamping device grips the yarn to cause said bail to draw yarn from a supply to form a first loop therein in advance of said clamping device and recede therefrom leaving a free loop forming a slack supply of yarn, said last-named means being such that the second loop-forming device remains out of engagement with the second loop during most of the cycle.

10. A yarn supplying mechanism comprising the combination of a clamping device through which the yarn passes, means for operating said clamping device to alternately grip and release said yarn, a first loop-forming bail pivoted in advance of said clamping device, means for rocking said bail while said clamping device grips the yarn to cause said bail to draw yarn from a supply to form a first loop therein in advance of said clamping device and recede therefrom leaving a free loop, said last-named means being such that the first bail remains out of engagement with the first loop while the clamping device releases the yarn, a second loop-forming bail pivoted in rear of said clamping device, and means for rocking said second bail while said clamping device releases the yarn to cause said second bail to engage and draw yarn from said first loop through said clamping device to form

15. A second loop in the rear thereof and to recede leaving a free loop forming a slack supply of yarn, said last-named means being such that the second bail is out of engagement with the second loop during most of the cycle.

20. 6. A yarn supplying mechanism comprising the combination of a clamping device through which the yarn passes, spring means acting to normally close said clamping device to grip the yarn, means for opening said clamping device against the tension of said spring means to release said yarn, a first loop-forming bail pivoted in advance of said clamping device, means for rocking said bail while said clamping device is closed to cause said bail to engage and draw yarn from a supply to

25. form a first loop therein in advance of said clamping device and to recede therefrom leaving a free loop, said last-named means being such as to cause the first bail to remain out of engagement with the first loop while the clamping device is open, a second loop-forming bail pivoted in the rear of said clamping device, and means for rocking said second bail while said clamping device is open to cause said second bail to engage and draw yarn through said clamping device from said first loop to form a second loop in

30. the rear of the clamping device and to recede therefrom leaving a free loop forming a slack supply of yarn, said last-named means being such that the second bail is out of engagement with the second loop during most of the cycle.

PAUL S. SMITH.
